HEAT EXCHANGER

Leslie E. Sebald, Ridgewood, N. J., assignor to The Griscom-Russell Company, New York, N. Y., a corporation of Delaware

Application March 11, 1939, Serial No. 261,256

6 Claims. (Cl. 257—239)

This invention relates to heat exchangers of the shell and tube type now extensively used as evaporators, condensers, water heaters, etc., in power stations, refineries, and in industrial establishments generally.

In apparatus of this kind one of the chief causes of breakdown and leakage, particularly when handling fluids of high temperature or pressure, are the strains to which the material and joints of the evaporator are subjected, due to the uneven expansion resulting from the wide differences in temperature which necessarily exist in different parts of the apparatus, and one object of the present invention is to provide a structure wherein the expansion of different parts of the apparatus to different degrees may take place with a minimum of strain upon the joints and other parts subject to breakage and leakage.

In apparatus of this kind, particularly when used for liquids and vapors containing corrosive impurities, frequent replacement of the heating tubes is necessary, and a second object of the invention is to provide a structure wherein the removal and replacement of the worn out tubes is greatly facilitated.

A further object of the invention is to provide a structure which is of compact design and dimensions, and in which a high rate of heat exchange per unit of heating surface is obtained.

In the accompanying drawings I have illustrated in detail certain embodiments of my invention which are now in commercial use.

In said drawings:

Fig. 1 shows in vertical longitudinal section an evaporator embodying my invention;

Fig. 2 is a transverse section on line 2—2 of Fig. 1 on a somewhat larger scale;

Figs. 3 and 4 are detail views of certain parts of the apparatus which will be later described; and

Fig. 5 shows in vertical section a water heater embodying my improvements.

Referring to the drawings, 1 indicates the shell of the apparatus, here shown as an elongated horizontal cylindrical shell designed to contain two heating units or tube bundles 2 and 2a respectively. As shown, the tube bundles 2 and 2a are composed of U-shaped tubes arranged so that the planes common to the axes of the two legs of the tubes are vertical and parallel.

The elongated horizontal shell illustrated has the advantage of large capacity in proportion to its diameter, and also the advantage that an apparatus of large capacity may be shipped as-

sembled on a single freight car, whereas shorter shells of greater diameter have to be made and shipped in sections. A heat exchanger which may be shipped assembled can be thoroughly tested before shipment and its performance assured, whereas apparatus which has to be erected at the place of installation is subject to defects in erection which are difficult to remedy.

One end 3 of the shell is preferably welded permanently to the shell body, whereas the other end 3a is bolted by a double series of staybolts (see Fig. 4) to the flange 5 formed integral with or welded permanently to the shell body. Any type of joint may of course be employed between the head and the body of the shell, but I prefer to use the joint illustrated for the reason that it will withstand high internal pressure without leakage. As shown, the cover 3a is provided with a heavy flange 6 which is set back from its edge. A second flange or ring 7 of much lighter weight is welded, as shown more particularly in Fig. 4, to the edge of the open side of the cover, this ring 7 being shaped to form a fluid-tight joint with the face of the flange 5. The ring 7 is welded at its inner edge only to the corresponding edge of the end cover 3a to thereby permit a limited relative movement of the end cover and the shell body 1 without disturbing the joint between the flange 5 and ring 7.

The joint between the flange 5 and ring 7 is maintained fluid-tight by one of the two series of bolts above referred to, namely, the smaller bolts 8 which terminate in the space between the ring 7 and flange 6. The other larger and heavier bolts 9 extend freely through holes in the ring 7, then through the heavy flange 6 on the end cover 3a, against the outer face of which the nuts on the ends of the bolts are drawn. By this construction the internal pressure on the end cover 3a places no strain on the bolts 8 which maintain the joint between the ring 7 and flange 5 fluid-tight. Instead the pressure on the end cover 4 is met entirely by the bolts 9 which are heavy enough to withstand the pressure without elongation beyond their elastic limit. This elongation of the bolts 9 does not tend to open the joint between the end cover and the shell as it is less than the movement permitted by the flexible joint between the ring 7 and the flange 6.

One of the principal features of my invention is the provision of a header made in separate upper and lower parts 4 and 4a, respectively. In the part 4 the upper ends of the tubes are expanded, while the ends of the lower portions of the tubes are expanded in the lower header sec-

tion 4a. The purpose and advantages of this divided head structure will be later pointed out.

The tube bundle is supported in the shell by rollers 10 (see Fig. 2) mounted for rotation in brackets 11 attached to the bottom edge of the header section 4a, said wheels resting, as shown in Fig. 4, on rails 12 extending the length of the shell. Additional rollers 13 are provided for supporting the looped end of the tubes, these rollers being attached as shown to the lower corners of tube-supporting plates 14 provided with holes for the tubes.

Each tube-supporting plate 14 is connected to its header sections 4 and 4a by means of longitudinal angles 25, six of which are preferably provided, as shown in Fig. 2. Also attached to the connecting angles 25 is an intermediate tube support 26, similar to the plate 14 but without the supporting rollers. By means of this construction the headers and tubes form a compact tube bundle which can be readily handled as a unit.

Over each tube bundle is a baffle 16 supported on the upper pair of angles 25, and an entrainment breaker or steam separator 17. Separate steam outlets for the two tube bundles are provided at 18 and 19, respectively. The supporting plates may with advantage be made in two sections bolted together in the same way as the two headers.

The two upper header sections are supported within the shell by means of connections 27 connected to the source of steam supply when the apparatus is used as an evaporator, and hangers 14a, while the lower header sections are attached to centrally located connections 15 for the discharge of the condensate in the tubes. The steam and drain connections extend through the top and bottom of the shell, respectively, in the same transverse vertical plane as the headers, and one advantage of the divided header construction is to permit the ready removal of the tube bundle from between these connections.

In removing the tube bundles the end cover 3a is removed and the joint between the lower connection and the lower header is then broken by the removal of the bolts. The lower header is then elevated by tightening the jack screws to a sufficient extent to permit tapered channel members 50 (see Fig. 3) which fit over the tracks in the shell to be pushed under the supporting wheels 10. The bolts are now taken out of the joint between the connection 27 and the upper header and one of the pins is removed from the hanger 14a. The upper header will thereupon sink of its own weight until it rests on the lower header section, thereby breaking the joint between this connection and the upper header. The tube bundle is now free to be rolled out of the shell on the tracks 12. After the tube bundle 2 is removed the tube bundle 2a may be similarly removed.

During the removal of the tube bundle 2a the channels 50 previously placed under the supporting rollers of the tube bundle 2 will be left in place and similar channel sections used for supporting the header of the tube bundle 2a, so that as the tube bundle 2a is shifted along the tracks it will be elevated as its headers pass over the drain connection of the tube bundle 2.

After the tube bundle is removed the replacement of a defective tube, no matter where it may be located in the tube bundle, can be accomplished without removing any of the other tubes. To this end the tube-supporting plates 14 and 26 are disconnected from the angles 25 and shifted

along the tubes toward the headers a sufficient distance to permit the outer tubes in the row containing the defective tube to be deflected sufficiently to get hold of the defective tube and withdraw it from the bundle. The legs of the tubes are not exactly parallel but are inclined slightly for drainage. Hence the tube supports 14 and 26 cannot be moved longitudinally of the tubes as a whole, but by making the tube-supporting plates in sections, as shown, the splice plates which connect the sections may be loosened, permitting the upper and lower sections of each plate to be shifted separately. The degree of inclination of the tubes is too slight to be illustrated in the drawings of the apparatus as a whole and as this feature is not claimed in this application, no detail view is included.

After the defective tubes are replaced the tube bundle may be replaced in the shell by reversing the procedure followed in removing the bundle. The channel-shaped lifters on the tracks will lift the headers to clear the lower connections, as the tube bundle is returned to position. The jackbolts will be screwed down to draw the two header sections together, and after the bundle is in position the steam inlet connection will first be made, the effect of which is to lift the headers slightly, thereby removing their weight from the channels. The channels are then removed from the tracks, and the jackbolts loosened to allow the lower header to drop down into position to tighten the lower connection.

Making the headers in separate upper and lower sections also serves to greatly reduce the strains which otherwise would result from expansion. In many fields of use of heat exchangers of this type there is a wide temperature difference between the upper and lower sections of the tube bundle. With the divided header here shown the upper header may freely expand both vertically and longitudinally to a greater extent than the lower header.

In order to permit free expansion of the shell I preferably support the shell fixedly at its median line only, as for instance, by a stand 20 bolted to the deck or floor on which the apparatus is mounted and welded to the under side of the shell 1. Near the ends of the shell are additional supports consisting of pedestals 21 welded to the under side of the shell and provided with bearing faces 22 resting on rollers 23 which in turn are maintained in position between the bearing 21 and the floor plates 24. The shell may thus freely expand at both ends without distortion to the full extent permitted by the steam and drain connections.

In Fig. 5 I have illustrated my improved heat exchange structure adapted for use in a high temperature-high pressure water heater. As will be observed, the structure is the same as the evaporator construction above described, except that the entrainment separator and plate baffle employed in the evaporator structure are not required in a water heater and these parts are therefore omitted, permitting the use of a larger tube bundle in the same diameter shell.

For convenience the water heater is shown as having but a single tube bundle, but it will of course be understood that the double tube bundle structure employed in the evaporator selected for illustration may be employed with equal advantage when the apparatus is used as a water heater.

In the water heater selected for illustration the water to be heated is admitted to the tubes

through the connection to the bottom header section as indicated on the drawing, thence passes through the tubes to the upper header section which is connected to the water discharge outlet. The heating steam which is at high temperature is admitted to the shell through the steam inlet in the top wall of the shell above the tubes, and is condensed on the tubes, thereby heating the water in the tubes. The condensate is drawn off through the condensate outlet. The unit described is designed for operating pressures in excess of 2000 pounds per square inch. These conditions of high temperature and high pressure expansion strains are very apt to result in breakdowns and leakage. In the design illustrated such strains are reduced to a minimum.

As previously stated, the apparatus disclosed in this application is particularly suited for high temperature-high pressure operating conditions.

In the preferred embodiment of my invention above described I have disclosed U-tubes which have been found economical and practical, but it will be understood that the invention is not limited to U-tubes as the various novel features of construction may be employed with advantage with straight tubes or bowed tubes having headers at both ends. It will also be understood that various other changes may be made in the construction disclosed without departing from the scope of the invention as defined in the appended claims.

I claim:

1. In a heat exchanger, the combination of a shell, a horizontal tube bundle supported in the shell, a header at one end of the tube bundle, said header being constructed of two relatively movable sections, said header sections being in the same vertical plane, inlet and outlet connections for said header, said connections extending upwardly and downwardly in the plane of the header sections, means for adjusting said sections toward and away from said connections in said common plane, supporting means for said headers adjacent the connection to the lower header section and means for altering the height at which said headers are supported adjacent said connection.

2. In a heat exchanger, the combination of a shell, a horizontal tube bundle comprising tubes and headers therein, supporting means within said shell for said tube bundle, a fluid connection at the bottom of said tube bundle, and means for altering the height at which said headers are supported within said shell adjacent said fluid connection.

3. In a heat exchanger, the combination of a

shell, a horizontal tube bundle therein, means comprising a track for supporting said tube bundle, a fluid connection at the bottom of said tube bundle, and a movable track section adapted to be mounted on the track for altering the height of the track surface adjacent said fluid connection.

4. In a heat exchanger, the combination of a shell, a removable cover at one end thereof, supporting tracks extending the length of said shell, a plurality of separate removable tube bundles supported in said shell on said tracks, separate inlet and outlet connections for said tube bundles each of said inlet and outlet connections comprising a fixed portion attached to the shell and a portion on the tube bundle movable therewith and positioned to register with the fixed portion when the tube bundle is in proper position in the shell, the fixed portions for the tube bundle adjacent the removable end cover being disposed out of the path of movement of the removable tube bundles in their movement out of the shell.

5. In a heat exchanger, the combination of a shell, a horizontal tube bundle supported in the shell comprising a plurality of tubes having inflow and return portions arranged respectively in parallel, separate headers for the inflow and return portions, each header comprising a substantially vertical tube sheet with the ends of the tubes fitted therein and cover sections enclosing the open ends of the tubes, said headers being mounted one above the other in the same vertical plane, inlet and outlet connections for said header, said connections extending opposite from each other in the plane of the header sections, and means for adjusting said headers toward and away from said connections in said common plane.

6. In a heat exchanger, the combination of a shell, a horizontal tube bundle supported in the shell comprising a plurality of tubes having inflow and return portions arranged respectively in parallel, separate headers for the inflow and return portions, each header comprising a substantially vertical tube sheet with the ends of the tubes fitted therein and cover sections enclosing the open ends of the tubes, said headers being mounted one above the other in the same vertical plane, inlet and outlet connections for said header, said connections extending opposite from each other in the plane of the header sections, and bolt means connecting said headers for drawing said headers towards one another.
